(57) **CLAIM**

The ornamental design for a laser level, as shown and described.

DESCRIPTION

FIG. 1 is a front view of a laser level according to the present invention.

FIG. 2 is a left side view of the laser level according to the present invention.

FIG. 3 is a right side view of the laser level according to the present invention.

FIG. 4 is a top view of the laser level according to the present invention.

FIG. 5 is a bottom view of the laser level according to the present invention.

FIG. 6 is a rear view of the laser level according to the present invention; and,

FIG. 7 is a perspective view of the laser level according to the present invention.
